Primary Examiner — Mary Ann Calabrese*Assistant Examiner* — Catherine Ho*(74) Attorney, Agent, or Firm* — Christine Flanagan(57) CLAIM

We claim the ornamental design for a label, as shown and described.

DESCRIPTION

FIG. 1 is a perspective view of a label, showing my new design;

FIG. 2 is a front view thereof;

FIG. 3 is a rear view thereof;

FIG. 4 is a left side view thereof;

FIG. 5 is a right side view thereof;

FIG. 6 is a top down view thereof; and,

FIG. 7 is a bottom up view thereof.

The broken lines are for the purpose of illustrating the environment of the design only and form no part of the claimed design.

1 Claim, 1 Drawing Sheet(56)
